(57) CLAIM

I claim the ornamental design for a vanity rack for hair accessories, as shown and described.

DESCRIPTION

FIG. 1 is a perspective view of a vanity rack for hair accessories showing my new design in use; the broken lines depict environmental structure for illustrative purposes only and form no part of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 4 Drawing Sheets

FIG. 1.

FIG. 5.

FIG. 7.
